UNITED STATES PATENT OFFICE.

WILLIAM H. GUY, OF DETROIT, MICHIGAN.

CUSHIONED SOLE AND HEEL FOR SHOES.

1,069,001.

Specification of Letters Patent.

Patented July 29, 1913.

Application filed January 14, 1913. Serial No. 742,028.

To all whom it may concern:

Be it known that I, WILLIAM H. GUY, a citizen of the United States, residing at Detroit, in the county of Wayne and State of Michigan, have invented new and useful Improvements in Cushioned Soles and Heels for Shoes, of which the following is a specification.

This invention relates to cushioned soles and heels for shoes, the object of the invention being to provide a construction of inner sole and heel, whereby air or other fluid or liquid may be confined therein to act as a cushioning medium.

12 A further object of the invention is to provide a cushioned inner sole or heel which is simple of construction, compact in form, adapted to be used without rendering the use cumbersome or bulky and in which the air or other fluid or liquid may be supplied in a ready and convenient manner.

The invention consists of the features of construction, combination and arrangement of parts hereinafter fully described and 25 claimed, reference being had to the accompanying drawings, in which:

Figure 1 is a vertical longitudinal section through a shoe showing the application of the invention. Fig. 2 is a sectional perspective view of the cushioning inner sole and heel and coating parts detached. Figs. 3 and 4 are similar views of an inner sole and the heel pad as adapted for independent use. Fig. 5 is a detail sectional view of the 35 valved nipple and air supply tube.

In the practical embodiment of my invention, the essential features of the invention may be embodied in an inner sole and heel connected for use in conjunction with 40 each other, or which are separate from and independent of each other, and the sole and heel may be adapted to be built into a shoe or to be applied in the form of pads to shoes already constructed. While, for purposes of 45 illustration, the inner sole and heel are so termed and independently described in the specification, it is to be understood that in the appended claim the term "sole" is intended to apply to the embodiment of the invention in any of the forms above described.

50 Referring to the drawing, 1 designates a shoe of any suitable construction, within which is arranged my improved cushioned inner sole 2 and cushioned heel 3, each of 55 which is shaped to conform to the part of the shoe in connection with which it is em-

ployed. As illustrated in the present instance, the cushioned inner sole and cushioned heel are disposed between the lining and fixed sole and heel of the shoe, but 60 they may be otherwise arranged as conveniences and circumstances may require.

The cushioned sole and heel are of generally similar construction, each comprising superposed plies 4 and 5 of suitable material, preferably a light layer of canvas saturated with rubber, or very thin layers of canvas or rubber suitably combined together. These plies are marginally united 65 in any preferred manner to form a shallow 70 chamber to receive the air or other cushioning medium. The plies 4 and 5 are connected at intervals throughout by resilient unions 6, of rubber or other suitable material, by which they are held from collapsing into a flat condition and maintained 75 in normal shape. These unions consist of corresponding semi-spherical projections upon the layers, which are arranged at intervals throughout the area thereof on the 80 interior of the air chamber, the correspondingly arranged projections of said layers being in contactual relation.

As shown in Figs. 1 and 2, the sole and heel sections are connected by a tube 7, 85 which extends over the instep of the sole, and the heel member 3 has connected therewith a tube 8 extending between the upper of the shoe and its lining to the counter, where said tube communicates with a check 90 valve casing 9 suitably fastened to the counter and communicating with the outside atmosphere. In said valve casing is a spring closed check valve 10, and if desired the casing may be provided with a closure 95 cap 11. The valve casing thus constructed provides a nipple by which the tube 8 may be connected with a pump to force air or other fluid into the elastic or cushioned sole and heel sections and confined therein to give 100 a cushioning action. The valve, however, may be of such a type as to enable air to be drawn into the sole and heel sections by collapsing the same under the pressure of the foot and then allowing said sections to expand to draw air therein. Other fluids or liquids may, however, be introduced through the tube to serve as the cushioning medium.

If desired, the cushioned inner sole and heel may be constructed independently of 110 each other, and each provided with a filling tube and valve, as shown in Figs. 3 and 4.

This allows them to be independently used within a shoe, as will be readily understood.

It is evident, therefore, from the foregoing description that the invention provides 5 a sole which is light, strong, durable and flexible, which is of minimum depth or thickness to adapt it to be used without rendering the shoe bulky or cumbersome, and which is designed to afford an easy and 10 comfortable cushioning action.

I claim:—

A cushioned sole for shoes comprising a body formed of superposed layers of material marginally connected to provide a 15 chamber of slight depth, one of said layers

being provided at intervals throughout the area thereof and on the interior of said chamber with substantially semi-spherical resilient projections, and the other of said layers being provided with corresponding 20 projections in contactual relation with said first-mentioned projections, and means whereby a cushioning medium may be introduced into said chamber.

In testimony whereof I affix my signature 25 in presence of two witnesses.

WILLIAM H. GUY.
